UNITED STATES PATENT OFFICE.

EDWARD R. AVERY, OF PONY, MONTANA, ASSIGNOR OF ONE-HALF
TO CHARLES ELMER MORRIS AND PHILIP HARRY GOHN, OF PONY,
MONTANA.

RAIL-JOINT FOR RAILWAYS.

SPECIFICATION forming part of Letters Patent No. 707,494, dated August 19, 1902.

Application filed April 30, 1902. Serial No. 105,335. (No model.)

To all whom it may concern:

Be it known that I, EDWARD R. AVERY, a citizen of the United States, residing at Pony, in the county of Madison and State of Montana, have invented certain new and useful Improvements in Rail-Joints for Railways, of which the following is a specification.

This invention relates to railway-rail joints, and has for its object to provide a device of improved and simple construction for connecting the meeting ends of the rails without employing bolts or fish-plates usually used for the purpose, the construction and arrangement being such that while the device effectually prevents lateral and vertical displacement of the rails it will permit of the expansion and contraction of the rails, due to variations in the temperature, without injury to the joints.

It also has for its object to provide improved means for automatically tightening up the joint should the parts become loose owing to the vibration caused by the passage of trains over the rails.

Finally, it has for its object to improve and simplify this class of devices generally.

To these ends my invention consists in the features and in the construction, combination, and arrangement of parts hereinafter described, and particularly pointed out in the claims following the description, reference being had to the accompanying drawings, forming a part of this specification, wherein—

Figure 1 is a perspective view of a railway-joint made in accordance with my invention. Fig. 2 is an end view of the same, showing the spring-plate. Fig. 3 is a view from the opposite side of the joint, showing the wedge in place. Fig. 4 is a top view of the chair with rails and other features omitted. Figs. 5 and 6 are detailed views of a wedge, showing the T-headed bolt.

Referring to the drawings, the numeral 1 indicates a railway-rail chair comprising a flat base 2, provided on its upper side with two flanges 3 and 4, which are undercut on their adjacent lower faces, as at 5 and 6, for the reception of the base-flanges 7 of the rails. The overhanging portions 8 and 9 of the flanges 3 and 4 are constructed to receive between them the webs 10 of the rails, and,

as shown in the drawings, the overhanging shoulder 8 of the flange 3 is parallel with and abuts the webs of the rails, while the corresponding shoulder 9 of the flange 4 is 55 tapered or inclined—that is to say, is formed obliquely to the webs of the rails or to the shoulder 8—and does not extend to the webs of the rails.

Fitted between the shoulder 9 and the adjacent sides of the webs of the rails is a tapered or wedge-shaped key 11, said key having approximately the shape of a trapezium in cross-section, or, in other words, said key gradually diminishes in size from one 65 end to the other and is inclined on its top and bottom faces to fit the under side of the tread of the rails and the upper sides of the base-flanges thereof, while its inner face is vertical to fit against the webs of the rails, and its 70 opposite face is inclined and tapered to fit the oblique shoulder 8. After the ends of the rails have been seated in the chair between the flanges 3 and 4 the wedge-shaped key is driven into place, tightly clamping the rails 75 in place.

Attached to the larger end of the flange 4 is a bracket-plate consisting of a flat plate 12, of resilient metal—such as tempered steel, for example—the end of which is slotted, as 80 at 13, for the purpose hereinafter explained, and projects inwardly beyond the end of the key 11. In the outer inclined face of the key 11, near its smaller end, is formed a T-shaped groove 14, in which is removably fitted a T- 85 shaped bolt 15, the threaded end of which projects through the slot 13 in the spring bracket-plate and has fitted thereon a nut 16, against which the spring bracket-plate bears.

After the rails have been inserted in the 90 chair and the key has been driven into place in the chair the nut 16 is tightened up, thereby placing the bracket-plate under tension and causing it to bear with a strong pressure against the nut. The spring bracket-plate 95 performs a twofold function. By pressing against the nut with a spring-pressure the threads of the nut are caused to bind against the threads of the bolt, and thereby tends to prevent the nut from unscrewing, and should 100 the key become loose through the vibration caused by the passage of heavy trains over

the rails the spring bracket-plate operates to instantly and automatically draw up the tapered key, so as to wedge it between the shoulder 9 of the flange 4 and the webs of the rails.

5 As shown, the chair is cast in one single integral piece and in practice may be formed of malleable iron or cast-steel, while the spring bracket-plate is preferably formed of tempered steel to give to it the necessary resiliency.

By means of my improved rail-joint I dispense entirely with the bolts and fish-plates usually employed for the purpose and provide a continuous and practically smooth and uninterrupted 15 surface for the car-wheels to run on, avoiding the customary pounding of the wheels on the abutting ends of the rails and the wear and noise resulting therefrom. At the same time the spring bracket-plate will yield sufficiently to accommodate the endwise movement of the rails caused by the contraction and expansion of the rails due to variations in temperature. By removably fitting the bolt in the key in the manner shown and

25 described should the bolt be broken from any cause a new bolt may be readily substituted.

Having described my invention, what I claim is—

1. A railway-chair provided with undercut flanges constructed to embrace the base-flanges and webs of two abutting rails, one of said flanges being parallel with the rail-webs and the other oblique thereto, a wedge-shaped key fitted between said oblique flange and 35 the rails, a slotted resilient bracket-plate fitted to the end of the oblique flange, a bolt fitted in the smaller end of the wedge-shaped key and projecting through the slot in the spring bracket-plate and a nut fitted on the bolt and bearing against the spring bracket-plate, substantially as described.

2. A railway-chair provided with undercut flanges constructed to embrace the base-flanges and webs of two abutting rails, one of 45 said flanges being parallel with the rail-web and the other oblique thereto, a wedge-shaped key fitted between said oblique flange and

the rails, a slotted resilient bracket-plate fitted to the end of the oblique flange, a bolt removably fitted in the smaller end of the wedge-shaped key and projecting through the slot in the spring bracket-plate, and a nut fitted on the bolt and bearing against the spring bracket-plate, substantially as described.

3. A railway-chair provided with undercut flanges constructed to embrace the base-flanges and webs of two abutting rails, one of said flanges being parallel with the rail-webs and the other oblique thereto, a wedge-shaped key fitted between said oblique flange and the rails, a slotted resilient bracket-plate fitted to the end of the oblique flange and projecting inwardly in front of the smaller end of the wedge-shaped key, a bolt fitted in 65 the smaller end of said wedge-shaped key and projecting through the slot in the spring bracket-plate, and a nut fitted on the bolt and bearing against the spring bracket-plate, substantially as described.

4. A railway-chair provided with undercut flanges constructed to embrace the base-flanges and webs of two abutting rails, one of said flanges being parallel with the rail-web, and the other oblique thereto, a wedge-shaped key fitted between said oblique flange and the rails, a slotted resilient bracket-plate fitted to the end of the oblique flange and projecting inwardly in front of the smaller end of the key, said key being provided on 75 the inner face of its smaller end with a T-shaped groove, a headed bolt removably seated in said groove and projecting through the slot in the spring bracket-plate, and a nut fitted on said bolt and bearing against 85 the spring bracket-plate, substantially as described.

In testimony whereof I affix my signature in presence of two witnesses.

EDWARD R. AVERY.
